DOLLY MOUNTED VACUUM CLEANER

Louis L. Otto and Stuart H. Jones, Muskegon, Mich., assignors to Clarke Floor Machine Division, Studebaker Corporation, Muskegon, Mich., a corporation of Michigan

Filed Sept. 12, 1966, Ser. No. 3,830

Term of patent 14 years

(Cl. D9—2)

FIG. 1 is a front perspective view of a dolly mounted vacuum cleaner showing our novel design;

FIG. 2 is a side-perspective view thereof; and

FIG. 3 is a fragmentary rear-elevational view thereof.

The side not shown has substantially the same appearance as the side shown except as indicated in the figures.

We claim:

The ornamental design for a dolly mounted vacuum cleaner, substantially as shown and described.
